UNITED STATES PATENT OFFICE.

FAY CHASE DARLING, OF WALTON, NEW YORK.

BATH AND BASIN FITTING.

Application filed February 8, 1923. Serial No. 617,896.

To all whom it may concern:

Be it known that I, FAY C. DARLING, a citizen of the United States, and a resident of Walton, in the county of Delaware and State of New York, have invented a new and Improved Bath and Basin Fitting, of which the following is a full, clear, and exact description.

This invention relates to new and useful improvements in bath and basin fittings, and it pertains more particularly to a stopper for the waste-pipe of such fittings.

It is one of the primary objects of the present invention to provide a receptacle for the reception of the stopper in order that the same may be concealed from view when not in use.

It is a further object of the invention to construct the device so that the stopper will be moved automatically to position within the receptacle.

It is a further object of the invention to provide the receptacle with a lid or cover which is adapted to engage the chain of the stopper to prevent automatic operation of the device when the stopper is positioned in the drain opening.

In carrying out the invention, a counter-weight is used, and it is a further object of the invention to provide means for preventing the counterweight from falling into an inaccessible position in case of breaking of the chain.

With the above and other objects in view, reference is had to the accompanying drawings, in which—

Fig. 1 is a detail sectional view of the overflow drain of a bathtub showing the manner in which the device is used in connection with a structure of this character;

Fig. 2 is a detail horizontal sectional view taken on the line 2—2 of Fig. 1.

In the drawings the reference character 30 designates a bathtub, and 31 designates the overflow drain thereof. Mounted over this overflow drain is a guard plate 32 pro-

vided with openings 33. A curved pipe 34 is employed, and extending through the curved pipe 34 and one of the openings 33 in the guard plate 32, is a chain 35. Secured to one end of the chain 35, is a stopper 36 and to the other end is secured a counter-weight 37. The reference character 38 designates an overflow pipe leading from an overflow drain, and mounted in the pipe is a guard 39 adapted to receive the counter-weight 37 and prevent the same from passing to an inaccessible point in the plumbing should the chain 35 become broken. As shown in Fig. 2, this guard 39 is provided with perforations 40 to permit of the passage of water therethrough.

The invention operates as follows:

When the stopper is removed from the drain opening in the tub 30, under the influence of the counterweight 37 the same will be moved upwardly of the tub until the counterweight 37 engages the guard 39.

What is claimed is:

1. In combination with a bath or basin fitting having a discharge opening and a stopper therefor and an overflow opening, a flexible member connected to the stopper, and a counterweight connected to said flexible member, said counterweight being adapted to move the flexible member through the overflow opening of the fitting to cause disengagement of the stopper from the discharge opening of said fitting.

2. In combination with a bath or basin fitting having a discharge opening and a stopper therefor and an overflow opening, a flexible member connected to the stopper, a counterweight connected to said flexible member, said counterweight being adapted to move the flexible member through the overflow opening of the fitting to cause disengagement of the stopper from the discharge opening of said fitting, and a guard for limiting the movement of the flexible member and counterweight.

FAY CHASE DARLING.
